(57) CLAIM

The ornamental design for an automatic hair washer, as shown and described.

DESCRIPTION

FIG. 1 is a front view of the automatic hair washer in accordance with my new design;

FIG. 2 is a back view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken lines in FIGS. 1, 2, 3, 4, 5 and 7 immediately adjacent to solid lines define the bounds of the claimed design; all other broken lines are for illustrative purposes only. None of the broken lines form a part of the present claim.
